UNITED STATES PATENT OFFICE

156,674

DRINK MIXER

Fred C. Schwanek, Chicago, Ill., assignor to Doremeyer Corporation, Chicago, Ill., a corporation of Illinois

Application March 12, 1948, Serial No. 145,049

Term of patent 14 years

(Cl. D44—1)

To all whom it may concern:

Be it known that I, Fred C. Schwanek, a citizen of the United States, residing at 5034 North Nashville Avenue, Chicago, county of Cook, and State of Illinois, have invented a new, original, and ornamental Design for a Drink Mixer, of which the following is a specification, reference being had to the accompanying drawings, forming a part thereof.

Fig. 1 is a side elevational view of a drink mixer embodying the invention;

Fig. 2 is a rear elevational view thereof;

Fig. 3 is a front elevational view thereof;

Fig. 4 is a top plan view thereof; and

Fig. 5 is a bottom view thereof.

The dominant feature of my design resides in the drink mixer shown in full lines.

I claim:

The ornamental design for a drink mixer, as shown and described.

FRED C. SCHWANEKE.
